(57) **CLAIM**

The ornamental design for a pool vacuum head as shown and described.

DESCRIPTION

FIG. 1 is a front perspective view of a pool vacuum head showing my new design;

FIG. 2 is a rear perspective view thereof;

FIG. 3 is a front view thereof;

FIG. 4 is a rear view thereof;

FIG. 5 is a left end view thereof;

FIG. 6 is a right end view thereof;

FIG. 7 is a top view thereof; and,

FIG. 8 is a bottom view thereof.

The broken lines illustrate portions and environment of the pool vacuum head and form no part of the claimed design.

1 Claim, 6 Drawing Sheets
